UNITED STATES PATENT OFFICE.

DONALD G. ROGERS, OF BUFFALO, NEW YORK, ASSIGNOR TO NATIONAL ANILINE & CHEMICAL COMPANY, INC., OF NEW YORK, N. Y., A CORPORATION OF NEW YORK.

PRODUCTION OF VAT DYESTUFFS.

No Drawing.

Application filed June 17, 1921. Serial No. 478,323.

This invention relates to the production of vat dyestuffs, and particularly to the dyestuff known chemically as N-dihydro-1.2-1'.2'-anthraquinonazine from beta-

5 aminoanthraquinone.

In the fusion of beta-aminoanthraquinone, as heretofore proposed, for the production of N-dihydro-1.2-1'.2'-anthraquinonazine, a quantity of caustic potash has been used 10 greatly in excess of that required for the reaction. This large excess of caustic potash involves a substantial element of expense and is undesirable from the standpoint of yield of the final dye; but it has nevertheless been considered necessary to use such an excess of the caustic potash in order to give sufficient fluidity to the melt 15 to allow suitable agitation at temperatures not too high for the process in question.

20 The present invention is based upon the discovery that the amount of caustic potash required in the fusion of beta-aminoanthraquinone for the production of N-dihydro-1.2-1'.2'-anthraquinonazine can be radically reduced in amount, and the fusion carried 25 out in a particularly advantageous manner by adding a suitable mineral oil to the reaction mass. I have found that by the use 30 of mineral oil, the amount of caustic potash can be reduced to 40% or less of the amount heretofore used. The mineral oil does not apparently enter into or affect the course of 35 the reaction in any objectionable way, and it may be readily recovered and used over again. It nevertheless enables the fusion mass to be kept sufficiently fluid so that it 40 may be suitably agitated.

In addition to the advantage of greatly 45 reducing the amount of caustic potash required, the addition of mineral oil to the reaction mass considerably reduces the time required for the completion of the process, greatly simplifies the operation and control of the process, as compared with the process 50 in which a large amount of caustic potash is used without the mineral oil or similar material, and produces a product which is in a high state of subdivision.

The mineral oil employed should advantageously have a suitable boiling point of 55 around 230° C. or somewhat higher, that is, at about the temperature at which the process is to be carried out. By using mineral oil of a boiling point corresponding to that

it affords an automatic temperature control of the reaction, inasmuch as the temperature will not exceed the boiling point of the mineral oil. A suitable mineral oil may be obtained from commercial kerosene by subjecting it to distillation and removing the fraction boiling below about 230° C. If steam distilled kerosene is used, the final dyestuff produced in the process can readily be freed from kerosene by steam distillation. Instead of using kerosene, other indifferent solvents or diluents can be used, for example, hydrocarbons which are liquid at relatively low temperatures and which have a boiling point above that of the temperature of reaction and which can be separated without difficulty at the end of the reaction.

The invention will be further illustrated by the following specific example:

220 liters of mineral oil, obtained from steam distilled kerosene, of a boiling point somewhat above 230° C. are heated to a temperature of from 220 to 225° C., 40 kilos of beta-aminoanthraquinone are added with 80 agitation, and then 7.5 kilos of potassium nitrate or chloride. 30-35 kilos of potassium hydroxide in granular, flake or powdered form are then gradually added while maintaining the temperature around 220° 85 to 225° C. The temperature is then raised to about 230° C. to complete the reaction which takes place with evolution of water vapor and with a change of color, passing from the orange of beta-aminoanthraquinone to the violet black of the condensation product. At the end of the reaction, the 90 fusion mass is cooled, the mineral oil filtered off, and the product worked up in the manner usually employed for the isolation and purification of this dyestuff.

During the addition of the caustic potash to the reaction mass, water vapor is evolved, and the temperature is lowered slightly thereby. This water vapor should be permitted to escape, that is, the reaction should be carried out without a reflux condenser, or if a reflux condenser is used it should be maintained at such a temperature that it will permit the water vapor to escape. Any mineral oil that distils over during the reaction can be suitably condensed and recovered.

In carrying out the process, the manner or order of admixing the ingredients can

be varied somewhat, for example, the potassium hydroxide and the potassium nitrate or chlorate may be added to the hot mineral oil, and the beta-aminoanthraquinone then added, or a mixture of the potassium hydroxide, potassium nitrate or chlorate, and beta-aminoanthraquinone can be added to the hot oil.

Different forms of apparatus are available for carrying out the process. The process thus can be carried out, for example, in a jacketed iron fusion kettle provided with an agitator, thermometer well, and a water jacketed condenser, and having a suitable outlet at the bottom.

The dyestuff produced as above described, when freed from alkali and impurities, is characterized by great fineness of grain, that is, it is obtained in a very finely divided state instead of large hard particles. The product is thus obtained in a physical condition which makes it of particular value for use in the production of dye pastes and powders. Dye pastes and powders made with the product of the above process have thus shown much greater tinctorial power than dye pastes and powders produced by the fusion of beta-aminoanthraquinone with caustic potash without the use of kerosene or similar material unless the latter dye pastes and powders are specially after-treated.

In the process of the above specific example the amount of caustic potash employed is only about 15% of that required in carrying out the fusion when no hydrocarbon is used; while the time required for the completion of the process is considerably less, for example, being only about 45 minutes for the completion of the operation after beginning to add the caustic potash as compared with about 3 hours or more when no hydrocarbon is employed. The process of the present invention also avoids objectionable foaming and enables the temperature to be easily controlled. The process also goes on without appreciable loss of ammonia such as takes place in the usual fusion process. The temperature of the reaction is also somewhat lower than when kerosene or similar hydrocarbon is not used; while a somewhat increased yield of the desired product is obtained.

It will thus be seen that the present invention presents many advantages over the processes of fusing beta-aminoanthraquinone with caustic potash heretofore known, among these advantages being the radical reduction in the amount of caustic potash used, a simplification in the operation of the process, a cutting down in the time required, the prevention of frothing, ease of control of the temperature, and the production of increased yields of a product in a granular form instead of in the form of hard lumps; moreover, the fusion melt, before filtration, can

be kept without being affected by atmospheric conditions, it being protected by the layer of mineral oil. These and other advantages are obtained by the use in the fusion process of a material such as mineral oil which is inert under the conditions used in the process, which can readily be obtained at a moderate expense and easily recovered for reuse, and which can be utilized to assist in controlling the temperature of the reaction, e. g., by using that portion of kerosene of appropriate boiling point corresponding to that of the desired temperature of reaction.

Owing to the finely divided and deflocculated condition in which the final product is obtained, and the greatly increased dyeing strength which it presents when used for dyeing purposes, I regard this form of the dyestuff as a new product. This product can be used without special treatment in printing and pigment work. Moreover, the dye pastes containing it seem to have a greater stability toward micro-organisms than other simple water pastes, perhaps due to a small amount of kerosene still contained in the product in an emulsified condition.

The term "fusion" is used to refer to the heating operation, whether or not actual melting of the ingredients or their solution in the solvent or diluent takes place.

I claim:

1. The improvement in the production of vat dyes which comprises subjecting a beta-aminoanthraquinone compound, to the action of caustic alkalis in the presence of an indifferent solvent or diluent.
2. The improvements in the production of vat dyes which comprises subjecting a beta-aminoanthraquinone compound, to the action of caustic potash in the presence of an indifferent solvent or diluent.
3. The improvement in the production of N-dihydro-1,2-1',2'-anthraquinonazin by fusing beta-aminoanthraquinone with caustic alkali which comprises carrying out the fusion with the addition of an indifferent diluent liquid at the temperature of the fusion and with the use of a radically smaller amount of caustic alkali as compared with the amount required when such indifferent diluent is not employed.
4. The improvement in the production of N-dihydro-1,2-1',2'-anthraquinonazin by fusing beta-aminoanthraquinone with caustic alkali which comprises carrying out the fusion with the addition of a hydrocarbon liquid at the temperature of the fusion and with the use of a radically smaller amount of caustic alkali as compared with the amount required when such hydrocarbon is not employed.
5. The improvement in the production of N-dihydro-1,2-1',2'-anthraquinonazin which comprises subjecting beta-aminoanthraqui-

none to fusion with caustic potash in the presence of a hydrocarbon or mixture of hydrocarbons which are liquid at ordinary temperatures and have a boiling point at or about the temperature of the fusion, whereby the reaction temperature is regulated by the boiling point of the solvent.

6. The improvement in the production of N-dihydro-1.2-1'.2'-anthraquinonazin which 10 comprises gradually adding caustic potash to a mixture of beta-aminoanthraquinone and mineral oil and heating the resulting mixture to a temperature of about 230° C. to complete the reaction.

15 7. The improvement in the production of N-dihydro-1.2-1'.2'-anthraquinonazin which comprises subjecting beta-aminoanthraquinone to the action of caustic potash in the presence of mineral oil at a temperature of 20 about 230° C., the mineral oil having a boiling point of about 230° C. or above.

8. The improvement in the method of producing N-dihydro-1.2-1'.2'-anthraquinonazin which comprises gradually adding about 30 25 kilos of caustic potash to a mixture of about 200 liters of mineral oil and 40 kilos of beta-aminoanthraquinone at a temperature around 220 to 225° C., raising the temperature to around 230° C. to complete the reaction and 30 permitting the water vapor evolved to escape from the reaction mass.

9. The improvement in the production of N-dihydro-1.2-1'.2'-anthraquinonazin which comprises subjecting beta-aminoanthraquinone to fusion with caustic alkali in the presence of an organic liquid chemically inac-

tive under the conditions of the fusion, whereby the amount of caustic alkali is greatly reduced from that required when such organic liquid is not employed.

40

10. As a new product, N-dihydro-1.2-1'.2'-anthraquinonazin in a finely divided and deflocculated condition, resulting from the fusion of beta-aminoanthraquinone with caustic alkali in the presence of an indifferent 45 diluent liquid at the temperature of reaction and at the temperature of the separation of the product therefrom.

11. The process of making indanthrene blue by heating beta aminoanthraquinone 50 with caustic potash and kerosene.

12. The process of making indanthrene blue by adding caustic potash at 220° C., to beta aminoanthraquinone suspended in kerosene.

55

13. The process of making indanthrene blue by heating beta-amino-anthraquinone and caustic potash at about 230° C. in the presence of an inert hydrocarbon diluent.

14. The process producing indanthrene 60 blue by first suspending or dissolving beta amino-anthraquinone in a mineral oil material, and then subjecting it to the action of caustic potash at about 230° C.

15. The process of making indanthrene 65 blue by the fusion of beta amino anthraquinone at about 230° C., with caustic potash suspended in kerosene and removing with the kerosene vapor the water-vapors evolved in the reaction.

70

In testimony whereof I affix my signature.
DONALD G. ROGERS.
